APPARATUS FOR CONVEYING EARTH AND
DETITUS THROUGH DIFFERENT PRES-
SURE AREAS OF TUNNELSLaurie F. Parker, Boston, Mass., assignor to Silas
Mason Company, Inc., East Boston, Mass., a
corporation of Delaware

Application February 17, 1932, Serial No. 593,460

6 Claims. (Cl. 61—84)

The object of the present invention is to provide means for continuously conveying earth and detritus in the cutting of tunnels under air pressure so that the cut material may be continuously carried from a high pressure area of the tunnel to low pressure areas, as, for example, atmospheric pressure areas, without changing those pressures during conveying of the material.

In brief, the method consists in conveying the cut material to a distributor adapted to successively direct the material to chambers wherein conveying means are adapted to receive the material and discharge it to a given point of discharge, the pressure within a chamber receiving the material from the distributor being higher than the pressure within said chamber at the time of discharge. As one chamber is receiving the cut material, a conveyor in a second chamber is discharging material and is open through the area of less pressure and shut off from the area of greater pressure, while said chamber is discharging, the second chamber is receiving and preparing for discharge so that when that point is reached, the first-named chamber again receives pressure and a load of material for subsequent discharge. The discharged material may be fed to a continuously moving conveyor upon which it is continuously received. In other words, the method consists in conveying material from a point of high pressure to a point of relatively low pressure, that the material is, or may be, discharged continuously without any interruptions due to opening and closing air locks.

The invention will be described with reference to the accompanying drawings, in which

Fig. 1 is a schematic perspective view of an embodiment of the invention.

Fig. 2 is a chart indicating the sequence of operation of the elements shown in Fig. 1.

Fig. 3 is a perspective view of a plurality of control disks, one for each conveyor tank for enabling the electrical control of the operations in sequence.

Fig. 4 is a plan view, partly in section, showing the discharge end of the apparatus illustrated in Fig. 1.

Fig. 5 is a sectional elevation on the line 5—5, Fig. 4.

Fig. 6 is a plan view, partly in section, of the apparatus.

Fig. 7 is a view in elevation of the apparatus.

Fig. 8 is a side elevation, partly in section, of the receiving end of the apparatus.

Fig. 9 is an enlarged transverse section through the casing 4 and the members below it.

Fig. 9a is a fragmentary perspective view of one of the walls of the distributor member and showing supporting plates for the discharge shutter.

Fig. 10 is an enlarged fragmentary sectional view through one of the distributor valve seats showing a portion of a valve and its lateral guide means.

Fig. 11 is an enlarged side elevation of the mechanism for actuating the distributor shutter.

Fig. 12 is a plan view of the same.

Fig. 13 is an enlarged elevation of the distributor valve seats, valves and operating mechanism, all of which may be identical with the discharge valve seats, valves and operating mechanism.

Fig. 14 is a front elevation of the structure shown in Fig. 13.

Referring to Fig. 1 of the drawings, 1 indicates a wall separating two sections of a tunnel, the section A being of higher air compression than the section B.

The letters and numerals employed in Fig. 1 will be used only for that figure, with the exception of the number 1 for the wall and A and B for the two sections of the tunnel. The letters and numerals in Fig. 1 refer to the chart showing the sequence of operations and to the controlling disk, Fig. 3, for a general and preliminary understanding of the sequence of operations later to be described.

The distributor

The distributor is designed to distribute the earth and detritus to conveyors located within conveyor tanks, and in the present embodiment, there are two conveyor tanks, 2 and 3. The distributor comprises a casing 4 which supports bearing members 5 for a shaft 6 carrying a pulley 7 for a conveyor belt 8 by means of which material is discharged into the casing.

Below and centrally of the casing is a horizontal support 9 to the right of which is a chute 10 leading to a valve casing 11 and to the left of which is a chute 12 leading to a valve casing 13. Valve casing 11 is disposed above a short conduit 14 communicating with the top of the conveyor tank 2 and valve casing 13 lies above a short conduit 15 communicating with the top of conveyor tank 3.

Above horizontal support 9 is a distributor shutter 16 carried by a shaft 17.

Secured to wall 4x of the casing are a plurality

of spaced blades 18, triangular in formation, their edges being partially cut away at 18^x to form shouldered seats for the upper margin of the distributor shutter, as shown in Figs. 9 and 9a, and above the shouldered seats is fixed plate 19. Similarly formed blades 18 and plates 19 are applied to wall 4^{xx} of the casing.

References to Figs. 11 and 12 will show that shaft 17 is mounted to oscillate in bearing members 21 carried by the frame 22, and secured thereto are spaced depending arms 23 each carrying inwardly projecting opposed flanged plates 24, the two sets of plates forming a raceway for the head 25 of a piston rod 26 adapted to be reciprocated within piston 21.

At one side of the piston is a pipe 28 and at the opposite side a pipe 28^x communicating with a pressure and relief valve 29 of a known construction and which is controlled by two switch boxes 30, 31. Box 30 is provided with a roll-end lever 32 and box 31 with a roll-end lever 33.

At the lower end of one of the arms 23 is a contact member 34^x which engages lever 33 when the distributor shutter is thrown to the left, thereby actuating valve 29 to release air pressure from pipe 28 and admit air pressure to pipe 28^x, causing piston rod 26 to move inwardly and thus swing the distributor shutter 16 to the right, this movement causing contact member 34^x to strike lever 32, thus actuating the mechanism of switch box 30 to reversely operate valve 29.

However, the throwing of one of the switches 32, 33, will not immediately cause operation of the valve 29^x, there being a time delay to permit discharge of material into the tank controlled by the distributor until the conveyor belt therein has carried the material forwardly until it is ready for discharge from the tank. To this end, the switches 30 and 31 will be in an electric circuit (not shown) also comprising an actuating solenoid 34 and the control disk will maintain the circuit open until the time delay has been completed, as will hereinafter be described more fully.

Solenoid 34 will be adapted to reciprocate soleil core 34^{xx} (Fig. 11) which is connected to one end of the lever 35, fulcrumed at 36 and connected intermediate its length with valve rod 29^x.

The distributor valves

As shown in Figs. 8, 9 and 10, each distributor chute 10 and 12 is provided with a valve casing 11 and 12; these casings being alike in construction and casing 11 being shown in longitudinal section in Fig. 8.

Within each casing is a gate valve 49 having laterally projecting ribs 49^x (Fig. 10) which enter slideways formed in the channelled bracket 50 at each side of the valve.

At the base of the casing is a plate 51 having an aperture in register with the aperture of short conduit 14 and the gate valve is adapted to slide upon the plate. The contacting surfaces of the plate and valve may be provided with anti-friction material as shown at 49^{xx}, Fig. 10, which will also serve to effect an air-tight seal when the gate valve is in closed position.

Each gate valve is connected to a piston rod 52 having a piston 53 adapted to reciprocate in a cylinder 54 to which is led compressed air through pipes 55, 56, leading to a two-way pressure and relief valve 57 having operative connections with a solenoid 58 which solenoid will be in a circuit including the controlling disks shown in Fig. 3 for timed operation.

As shown in Fig. 13, each gate valve will, in its

reciprocation, close a switch member, also in the circuit, at the end of a closing movement and at the end of an opening movement of the valve. To this end, each gate valve has connected thereto a rod 59 having thereon a contact member 60 adapted to engage the arm 61^x of switch 61 when the gate valve approaches the end of its closing movement. Rod 59 will also carry a contact member 62 adapted to engage arm 63^x of switch member 63 when the gate reaches the end of its opening movement. Inasmuch as the conveyor and one tank is receiving material at the time when the second tank is discharging material, the gate valves reciprocate reversely one to the other, 15 one gate being open while the other is closed.

Reference to Fig. 13 will show that the lower gate, which will control discharge chute 10 is open and that rod 59 has been brought into position to actuate the arm of switch member 63, thus closing the circuit except for the break therein due to the position of the control disks shown in Fig. 3 which disks at the proper moment will complete the circuit and cause solenoid 58 to be energized to act upon valve 57 for the admission of compressed fluid through pipe 55 to the rear of the piston causing the piston rod to advance with the gate and bring the gate to closed position shutting off tank 2 from the distributor. The electrical circuit and construction of the solenoid and valve form no part of the present invention, and are not shown in detail.

During the operation of the gate valve in each case either upon opening or upon closing the valve, or during both operations, means are provided for discharging blasts of air longitudinally of the valve casing in order to clear away particles of dirt which may lodge upon exposed surfaces thereof. To this end, there is disposed transversely of the valve casing at one end thereof, a pipe 64 apertured to permit the passage of blasts of air and fed by piping 65 and leading to the relief or discharge ports of valves 57, so that blasts of air will be ejected from pipe 64 upon both the closing and the opening of each valve 49. The pipe connections intermediate apertured pipe 64 and valves 57 are shown more particularly in Figs. 13 and 14.

The tank conveyors

Any suitable conveyor may be used in each tank and the conveyor belt may be driven by any suitable means. In the present embodiment, I have shown for each tank end rollers 37 and 38 over which the belt may travel and a plurality of guide rollers 39, 39^x for supporting and guiding the belt in its travel, the belt being driven through rotation of the sprocket 40 carried by shaft 41 upon which roller 38 is mounted, the sprocket being connected by a chain 42 with a sprocket 43 on a shaft 44 driven by rotation of a sprocket 45 which in turn is driven by belt 46 with a sprocket on a shaft 47 driven by suitable speed reduction gearing from a motor 48. The motor is preferably a two-speed motor and will be controlled by the control disks of Fig. 3 through any suitable instrumentalities so as to have a period of low speed and a period of relatively high speed for the purpose hereinafter set forth.

The conveyor tank discharge mechanism

The discharge mechanism for each tank is the same in construction.

Referring to Fig. 5, with reference to tank 2, it will be seen that below the discharge end of 75

the conveyor mechanism in the tank and adapted to receive material therefrom is a chute 66 adapted to discharge within a valve casing 67 similar to each of the gate valve casings 11 and 13 and having therein a gate valve 68 adapted to be reciprocated by a piston rod 69, the piston 69^x of the rod being disposed within a cylinder 70.

At one end of the cylinder is a pipe 71, for compressed air, and at the opposite end a pipe 72 for said compressed air, the pipes leading to valves 73 operated by a solenoid in box 74.

Below the valve casing and in register with chute 66 is a conduit 75 adapted to discharge upon conveyor belts 76. The gate valve in its movement will be guided by guide brackets 77 into channels of which the gate valve will be guided in the same manner as gate valves 49 are guided by the guide brackets 50.

Each gate valve 68 will have connected thereto a rod 81, Fig. 4 having thereon two contact members 79 and 80. When the gate valve is moved to closed position, contact member 79 will throw switch arm 81^x of switch 82 to close the switch preparatory to an opening movement of the gate valve and when the gate valve is moved to open position, contact member 80 will throw arm 83 of switch 84 to close the switch preparatory to a closing movement of the gate valve. Both movements are delayed however, by the control disks in Fig. 3 so that when in the continuous rotation of the latter, the proper circuit is momentarily closed, and the proper solenoid 74 will be actuated. In such actuation pressure will be relieved from cylinder 70 and reversely directed pressure emitted through one of the pipes 71 or 72. The arrangement is such that when the solenoid is energized it will actuate the valve 73 to open one of the pipes 71, 72, to the atmosphere so as to remove air compression back of piston 69^x, the latter being at one end of the cylinder and will admit compressed air to the cylinder to the second of said pipes for movement of piston 69^x in a direction opposite to that in which it was previously moved but when the solenoid is de-energized, a reverse action will take place, the valve being a four-way solenoid valve, *a* being, for example, a pressure inlet and *b* exhaust as to both the distributor valves 29 and the discharge valves 73.

50 The pressure system for the tanks

Referring to Fig. 6, it will be seen that an air pressure switch tank is provided at 85 having a pipe 8 leading to a pressure inlet valve 87 for tank 2 and a pipe 6 leading to a pressure inlet valve 88 for tank 3. Adjacent pressure inlet valve 87 is a pressure outlet valve 89 and adjacent pressure inlet valve 88 is a pressure outlet valve 90. These valves are used for compressing and decompressing the conveyor tanks. All of the valves 87 to 90 inclusive, are preferably hydraulic thruster valves employing a motor *c* (Fig. 7) for actuating an impeller to cause a piston to rise which will actuate valve lever *d* in each case.

65 General operation

As hereinbefore explained, the sequence of operation of the mechanism for each tank is timed and the timing means may be a rotating control disk for each electrical circuit as indicated schematically in Fig. 3, wherein the disk 91 is for control of the tank 3 and 92 for control of tank 2.

Assuming that the complete cycle of operation is set for 160 seconds, the operation is started by mechanism for rotating the control disks in the

direction of the arrow, Fig. 3, so that they will complete their rotation in said time. These disks will have spaced cams for actuating circuit closers or will otherwise be adapted to close a plurality of circuits successively. These cams are indicated by the circuit indications MD, CL, etc., on disk 91, and MD', R', D', etc. on disk 92 of Fig. 3.

The first action of the control disk will be to close the circuit MD leading to motor 48 for rotation of the conveyor within tank 3 at slow speed, 10 it being assumed that said tank has previously been compressed, and close circuit MD' leading to second motor 48 for operating the conveyor within tank 2 at high speed. It will be assumed that the conveyor belt in tank 2 will be covered 15 with material to be discharged from a point adjacent discharge chute for that tank to a point near the distributor. The next action of the control disk will be to close circuit L leading to switch 61 and solenoid 58 for tank 3, the solenoid acting 20 upon valve 57 to admit compressed air to pipe 59, piston 53 and rod 52 being operated thereby to open the receiving gate valve 49 for tank 3; and simultaneously the control disk acts to close circuit D', opening the discharge gate valve 68 for 25 tank 2. Due to the high speed of its motor, the conveyor belt for tank 2 will move forward rapidly discharging its contents through the open discharge gate valve 68 for said tank 2 whilst the conveyor belt for tank 3 is receiving material. 30 Upon the discharge of all the material from the conveyor belt in tank 2, the disks close circuit V and D' thereby swinging the distributor gate for distribution to tank 2 and closing the discharge gate valve for tank 2. 35

The disks then close circuits L and C' thereby closing distributor gate valve for tank 3 and opening the compressor air valve for tank 2, whereby the pressure in tank 2 is raised to that of section A of the tunnel in advance of wall *f*. The disks 40 then close circuits R and MD' thereby opening pressure release valve for tank 3 and operating the conveyor motor for tank 2 at slow speed.

The next action of the control disks is to close circuits MD and L', thereby operating the motor for conveyor belt in tank 3 at high speed and opening the distributor valve gate for tank 2. 45

The next action of the control disks is to close circuits D and V, thereby opening discharge gate valve for tank 3 and swinging distributor shutter to discharge into tank 3. 50

The next action of the control disks is to close circuits D and L' closing the discharge gate valve for tank 3 and closing the distributor gate valve for tank 2. 55

The next action of the control disks is to close circuits C and R', thereby opening the compressed air valve for tank 3 to compress said tank and opening the air release valve for tank 2 thereby de-compressing said tank. In other words, for each tank, the valve operations follow in sequence.

The conveyor belt starting at slow speed, the distributor gate is opened, and its distributor shutter thrown to enable discharge into the tank. 65 When the belt has received its discharge of material, the distributor gate valve is closed, and thereupon the air release valve is opened, decompressing the tank.

The motor is then run at high speed, the discharge gate opened and after the material is discharged, the gate is closed; the closing of the discharge gate valve enables re-compression of the tank and the compressed air valve is opened 70 75

for that purpose, whereupon, the motor may be run at slow speed, the distributor gate opened, the distributor shutter moved to proper position and the operations following in their proper sequence.

In Fig. 1, the letters indicating circuits shown on the chart of Fig. 2 and disks of Fig. 3, are used in connection with leading lines to the various elements at the circuits control.

10 It will be understood that various modifications may be made in the form and arrangement of the elements comprising the embodiment illustrated in the drawings, the air jet arrangement for clearing the gate valve and its casing of earth 15 shown in Fig. 13 as applied to the gate valves for the distributor, may be duplicated for the gate valves at the discharge ends of the tanks as indicated in dotted lines, Fig. 4. If desired, more than two tanks may be employed, and the means for 20 conveying earth and detritus through the tanks may be widely changed from that illustrated in the drawings, as, for example, through the provision of screw propelling means, although I have found that belts function satisfactorily. If desired, the gate valves may be operated mechanically 25 through levers and a mechanical control can be substituted for an electrical control. These and other modifications are within the purview of those skilled in the art, what I claim and desire to 30 secure by Letters Patent, being as follows:—

1. In apparatus for conveying material from a high pressure area to a low pressure area, and in combination with a tunnel bulkhead, of two air pressure cylinders extending through said bulkhead, each cylinder having a receiving aperture near one end thereof and a discharge aperture 35 near the opposite end thereof, a traveling conveyor within each chamber for conveying material longitudinally thereof, gate valves for the receiving and discharge apertures of said chamber, a hopper, chutes connecting the hopper with said receiving apertures of the chambers, a shutter intermediate said chutes and the hopper and movable to positions for alternately closing and 40 opening the chutes relatively to the hopper, and power means for operating said shutter.

2. Apparatus constructed in accordance with claim 1 in combination with means for supporting the shutter in each of two positions relatively to the hopper, said means comprising a plurality of spaced blades.

3. Apparatus constructed in accordance with claim 1, in combination with means carried by the hopper for supporting the shutter in each of two positions, said means comprising a plurality of opposed sets of blades, the blades being each formed with a reduced section provided with an overlying shoulder, the shutter abutting the shoulders of a set of blades in each position, and

a plate supported by each set of blades above the shoulders thereof.

4. In apparatus for conveying material from a high pressure area to a low pressure area, and in combination with a tunnel bulkhead, of two air pressure cylinders extending through said bulkhead, each cylinder having a receiving aperture near one end thereof and a discharge aperture near the opposite end thereof, a traveling conveyor within each chamber for conveying material longitudinally thereof, gate valves for the receiving and discharge apertures of said chambers, means for delivering material to the cylinders alternately, means for reciprocating the gate valves and a two-speed motor drive for each traveling conveyor whereby the conveyor may receive material during its movement at relatively low speed and may discharge material during its movement at relatively high speed.

5. In apparatus for conveying material from a high pressure area to a low pressure area, and in combination with a tunnel bulkhead, of two air pressure cylinders extending through said bulkhead, each cylinder having a receiving aperture near one end thereof and a discharge aperture 25 near the opposite end thereof, a traveling conveyor within each chamber for conveying material longitudinally thereof, a casing disposed above each cylinder receiving aperture, a gate valve mounted in said casing and adapted for 30 movement to close and open said receiving aperture, power means for operating said gate valves, a hopper, two depending chutes leading from the hopper, each chute being connected with one of said casings, a shutter pivotally mounted intermediate the hopper and the chutes, power means for swinging the shutter on its pivot to alternately close and open each chute, a casing communicating with each discharge aperture, a gate valve mounted in each of the last named casings and 40 power means for operating the last named gate valves.

6. In apparatus for conveying material from a high pressure area to a low pressure area, and in combination with a tunnel bulkhead, of an air pressure cylinder extending through said bulkhead, said cylinder having a receiving aperture at one end thereof and a discharge aperture at the opposite end thereof, a traveling conveyor within the chamber for conveying material longitudinally thereof, a casing carried by the cylinder at the receiving aperture, a gate valve within said casing, a casing carried by the cylinder at the discharge aperture and a gate valve in said casing, power means for operating said gate valve, and means for driving said traveling conveyor with an initial relative low speed and a succeeding relative high speed.

LAURIE F. PARKER.
